COMBINED CLOSURE CAP AND DISPENSER

James Donald Smith, Stroudsburg, Pa., and Seymour Rappoport, Rumson, N.J., assignors to Ronson Corporation, Woodbridge, N.J., a corporation of New Jersey

Filed Feb. 13, 1961, Ser. No. 63,929

Term of patent 14 years

(Cl. D58—26)

Tiq. 1.

Tiq. 2.

Tiq. 4.

Tiq. 3.

FIG. 1 is a side elevation of a combined closure cap and spout embodying our new design.

FIGS. 2, 3 and 4 are an end elevation as seen from the left of FIG. 1, a top plan view and a perspective view thereof, respectively.

FIG. 5 is a side elevation of a modified form of the combined closure cap and spout shown in FIG. 1.

FIGS. 6, 7 and 8 are an end elevation as seen from the left of FIG. 5, a top plan of FIG. 5 and a perspective view of FIG. 5, respectively.

We claim:

The ornamental design for a combined closure cap and dispenser, substantially as shown and described.
